DESIGN FOR A BODY BELT

Lorain C. Medearis, Storm Lake, Iowa

Application November 29, 1937, Serial No. 73,250

Term of patent 7 years

To all whom it may concern:

Be it known that I, Lorain C. Medearis, a citizen of the United States of America, residing at Storm Lake, in the county of Buena Vista, and State of Iowa, have invented a new, original, and ornamental Design for a Body Belt, of which the following is a specification, reference being had to the accompanying drawing, forming a part thereof.

In the drawing:

Figure 1 is a plan view of a body belt, showing my new design, and

Figure 2 is an edge view thereof.

My design is characterized by the imperforate pad outlined by stitching and the perforations along the upper and lower edges of the belt following the contour thereof in combination with the specific belt, as shown.

I claim:

The ornamental design for a body belt, as shown and described.

LORAIN C. MEDEARIS.
